UNITED STATES PATENT OFFICE.

CHARLES J. OLSEN, OF NEW YORK, N. Y.

ROWING-BOAT.

1,273,176.

Specification of Letters Patent. Patented July 23, 1918.

Application filed December 4, 1916. Serial No. 134,907.

To all whom it may concern:

Be it known that I, CHARLES J. OLSEN, a citizen of the United States, and a resident of New York, borough of Brooklyn, county of Kings, and State of New York, have invented a certain new and useful Improvement in Rowing-Boats, of which the following is a full, clear, and exact specification.

10 This invention relates more particularly to a class of boats.

My invention has for its object primarily to provide a rowing boat whereby a person who may be unskilled or skilled in the art 15 of rowing may conveniently operate the oars for propelling the boat, and which is of a form so that the oars will be prevented from becoming accidentally displaced from the hull of the boat to avoid being lost especially when the water is rough. The invention consists essentially of a hull with oars fulcrumed at opposite parts of its sides so as to be moved rotatably as well as backwardly and forwardly, and the oars are connected by an operating bar so that when 20 swung backwardly the oars will be partially rotated to cause their blades to simultaneously cut the water and when swung backwardly the oars will be reversely rotated to take the pressure of the water.

Other objects of the invention are to provide elements which connect the operating bar to the oars so that the bar will be adjustable to allow the boat to be rowed backwardly as well as forwardly; and to provide 35 retainers for holding the oars to the hull against accidental displacement.

A practical embodiment of the invention is represented in the accompanying drawing 40 forming a part of this specification in which similar characters of reference indicate corresponding parts in all the views, and will then be pointed out in the claims at the end of the description.

45 In the drawing, Figure 1 is a top plan of one form of rowing boat embodying my invention.

Fig. 2 is a side elevation of the boat.

Fig. 3 is a fragmentary view showing a 50 top plan of one of the elements for adjusting the oars of the boat as well as one end of the operating bar connected thereto, and

Fig. 4 is a fragmentary view, showing a

top plan, partly in section, of one of the retainers for movably holding the oars to the 55 hull of the boat.

The boat has a hull 10 which may be of any suitable shape and size having a round, or flat bottom with a suitable number of seats, as 11, therein for accommodating a 60 number of persons, and the boat is of a form adapted to be propelled by one pair, or a number of pairs of oars, as 12 and 13. Both of the oars 12 and 13 are preferably alike in 65 formation, each having a blade 14 on the lower end of a bar 15 which is of a length so that the upper end parts of the bars of both oars extend above the hull 10. When the boat is propelled by a single pair of the oars they are arranged on alinement at the 70 central parts of the sides of the hull so that the blades may be swung backwardly and forwardly as well as rotatably to alternately take and cut the water in the usual manner of rowing a boat.

75 The oars of this boat are preferably disposed vertically, and to hold the oars operatively against accidental displacement to the hull, retainers, as 16 and 17, are provided. Each of these retainers has a sleeve 80 18 through the passage of each of which is movably guided the upper part of the bar 15 of each of the oars so that the upper ends of the bars will extend some distance 85 above the sleeves, and these sleeves are formed with substantially semi-circular peripheries. The sleeves 18 are arranged so that their straight edges abut against the sides of the hull of the boat, and each of these sleeves is pivoted, at 19, to a plate 20 90 on the side of the hull 10 to allow the sleeve to be swung as well as the oar backwardly and forwardly toward and from the bow of the boat and vice versa. The sleeves are arranged so that their upper portions extend 95 above the hull of the boat, and on the top of each sleeve is a stationary plate 21, and both of these plates may be approximately oval in shapes of larger diameters than the sleeves as well as being arranged whereby 100 opposed parts thereof overhang the interior of the hull 10. The part of each bar 15 of the oars adjacent to the lower end of its sleeve is movably guided through an elongated strap 22 provided on the plate 20 of 105 its respective retainer so as to extend lat-

erally from the side of the hull, and rigidly secured on each bar under its strap is a sleeve 23. The sleeves 23 are larger than the passages through the straps 22 to prevent the oars from accidentally moving upwardly through the straps and through the sleeves 18.

The oars are operated to propel the boat by a bar 24 disposed between the upper ends 10 of the oars transversely of the interior of the hull 10 so that one or more persons in the boat may push this bar backwardly and forwardly. Extending from one end of the bar 24 is a loop, as 25, and projecting from 15 the opposite end of the bar is an eye 26. Serving to operatively connect the bar 24 to the oars whereby the bar may be adjusted for moving the oars to propel the boat backwardly as well as forwardly, elements, or 20 eccentrics, as 27 and 28, are provided. Each of the eccentrics 27 and 28 is in the form of a plate, or disk preferably of somewhat a pear-shape, and through the center of the enlarged portion of each disk is a hole 25 through which the upper end of one of the oars rotatably protrudes. Both of the disks movably rest upon the plates 21 of the sleeves 18 of the retainers 16 and 17, and projecting upwardly from the reduced part 30 of each disk, or eccentric is a pin 29. The pin 29 of the disk 27 is disposed through the eye 26 of the operating bar 24, while the pin 29 of the disk 28 is disposed through the loop 25 of the bar. Projecting upwardly 35 from each of the disks, or eccentrics is a pair of spaced pins 30, and on each of the disks in spaced relation to these pins is a second pair of spaced pins 31 also extending upwardly. On the oar 12 is a laterally projecting pin 32 for removable insertion between the pins of each pair of the disk 27, and on the oar 13 is a similar laterally extending pin 33 adapted to be removably accommodated between the pins of each pair 40 of the disk 28. The disks, or eccentrics being rotatable on the oars the insertion of the pins 32 and 33 of the oars between the pairs of pins of the disks will cause the oars and the disks to be rotatably moved in unison 45 when the bar 24 is operated, and the pins 32 and 33 also serve to prevent the oars from accidentally sliding downwardly through the disks and through the sleeves 18.

The pairs of the pins 30 and 31 of each of the disks or eccentrics 27 and 28 are relatively arranged so that when the pins 32 and 33 of the oars are interchangeably inserted from one pair of the pins to the other pair of each disk the oars will be revolvably 50 adjusted a distance approximately one-fourth of a circle, and by eccentrically connecting the bar 24 to the oars in this manner when the operating bar is moved forwardly and backwardly the oars will be partially rotated. Also projecting upwardly 55

from the plate 21 of each of the sleeves 18 are two spaced pins, or stops 34 and 35, and each pair of these pins are arranged on the plate so that the disks, or eccentrics will be limited to circumferential movements of 70 substantially one-half a circle.

To operate the oars for rowing the boat forwardly the oars are rotatably adjusted so that their pins 32 and 33 are disposed between the pairs of pins 31, of the disks or eccentrics 27 and 28 which are opposed to the stern of the boat. The bar 24 is then swung so that the eccentrics 27 and 28 will be in contact with the pins 35 of the stationary plates 21 which are also in opposed relation to the stern of the boat. When the bar 24 is moved toward the bow of the boat the blades of the oars will take the water for propelling the boat forwardly, and with the stroke of the oars the disks 27 and 28 80 will be rotatably swung to the second pair of pins 34 of the stationary plates 21. The oars will then be rotated about one-fourth of a circle to cause their blades to cut the water when the bar 24 is pulled reversely toward the stern of the boat. By repeating this operation of the bar 24 the boat will be easily rowed forwardly. The boat may be rowed in a reverse direction by turning the oars so that the pins 32 and 33 will be 90 shifted between the pairs of the pins 30 of the disks 27 and 28, and when the bar 24 is then reversely operated the boat will be rowed backwardly. Thus a simple and efficient boat is provided which may be easily 95 and safely rowed by one or more persons whether skilled or unskilled in the art of handling this class of boats.

In the foregoing description, I have embodied the preferred form of my invention, 105 but I do not wish to be understood as limiting myself thereto, as I am aware that modifications may be made therein without departing from the principle, or sacrificing any of the advantages of this invention, 110 therefore I reserve to myself the right to make such changes as fairly fall within the scope thereof.

Having thus described my invention, I claim as new and desire to secure by Letters 115 Patent:

1. In a rowing boat, a hull, two sleeves one pivoted to opposite parts of the sides of the hull so as to be swung backwardly and forwardly, two oars one rotatable in each sleeve and movable with the sleeve, an operating bar, two eccentrics one pivoted to each end of the bar, and both eccentrics being adjustably connected to the oars whereby the oars when the bar is moved backwardly will be partially rotated to cause their blades to simultaneously cut the water and when the bar is moved forwardly the oars will be reversely rotated to take the pressure of the water, and means on the ec- 125 130

centrics whereby the oars may be adjustably arranged to cause the boat to be rowed backwardly.

2. In a rowing boat, a hull, two plates 5 one fixed on opposite parts of the hull of the boat, two straps on each plate, two sleeves one pivoted to each of the fixed plates so as to be swung backwardly and forwardly, two oars one rotatable in and movable with each 10 sleeve as well as being movably disposed in each of the straps, an operating bar, two eccentrics one pivoted to each end of the bar, and both eccentrics being adjustably connected to the oars whereby the oars when

the bar is moved backwardly will be partially rotated to cause their blades to simultaneously cut the water and when the bar is moved forwardly the oars will be reversely rotated to take the pressure of the water, and means on the eccentrics whereby the 20 oars may be adjustably arranged to cause the boat to be rowed backwardly.

This specification signed and witnessed this 2nd day of December, A. D. 1916.

CHARLES J. OLSEN.
